Nes. 771

Nicholas Muller of New York, N. Y.
Letters Patent No. 771. Dated April 1, 1856.

The schedules referred to in these Letters Patent, and making part of the same.

To all whom it may concern:

Be it known that, I, Nicholas Muller, of the City, County and State of New York, have invented or produced a new and original design for block base fronts; And I do hereby declare that the following is a full and exact description of the same, reference being had to the annexed drawings making a part of this specification, in which,

Fig. 1. is a front view of a clock case, showing my improved design.

Fig. 2. is a side view of the front of the clock case.

Fig. 3. is a horizontal section of ditto.

A, represents the front of a clock case. B, is the circular opening made through it for the dial of the clock.

C, represents a female figure, the Goddess Juno, which is placed at one side of the opening, B; the right arm of the figure resting upon the upper part of the rim, (a), of the opening, B.

D, represents a peacock, which is at the opposite side of the opening, B; and E, represents the foliage of a tree, which forms the top part of the case front; the foliage being directly back of the body of the peacock and the head of the female figure; the body of the peacock and the head of the female figure projecting in relief from the foliage.

(The sides of the case front as well as its lower end or base, is formed of scrolls, shells, etc, as represented in Fig. 1.

What I claim as new, and desire to secure by Letters Patent, is

The female figure, C, peacock, D, and foliage, E, when arranged and combined as herein shown, to form an ornamental design for a Clock case front.
